UNITED STATES PATENT OFFICE.

DANIEL A. WOODBURY, OF ROCHESTER, NEW YORK.

CRANK-SHAFT.

SPECIFICATION forming part of Letters Patent No. 357,884, dated February 15, 1887.

Application filed March 12, 1886. Serial No. 194,953. (No model.)

To all whom it may concern:

Be it known that I, DANIEL A. WOODBURY, a citizen of the United States, residing in the city of Rochester, in the county of Monroe and State of New York, have invented a new and useful Improvement in Crank-Shafts, of which the following is a specification.

My invention relates to the balancing of crank-shafts by means of counterbalancing-disks secured to the cranks in the planes thereof; and the object of the invention is to provide a better means for fitting and securing said disks to the cranks, whereby the former may be readily taken off the latter when necessary and replaced without refitting, the seat or bearing of the disk upon the crank and the fastening for the disk being such that said disk, when replaced after being taken off, shall run true and be concentric with the journals 20 of the shaft.

This improved means for balancing cranks is applicable whether there are one or more cranks upon the same shaft, and without regard to the angle they make with each other, 25 or whether the cranks are of the same or different throw, a balancing-disk being fitted to each.

Referring to the drawings, Figure 1 is an end view of a shaft, showing the crank and balancing-disk in side elevation, said disk being secured to place upon the crank; Fig. 2, a section through the center of the crank and disk by a plane coinciding with the axis of the shaft, taken as upon the dotted line $x-x$ in 30 Fig. 1, and viewed as indicated by the arrow pointed thereon; and Fig. 3, a section of the parts taken through the center of the shaft at right angles to the section shown in Fig. 2, as upon the dotted line $y-y$ in Fig. 1, and viewed as indicated by the arrow pointed thereon. The remaining seven figures are drawn to show modifications in the manner of securing the disk in place upon the crank.

Referring to the parts of the device, A is 45 the shaft, B the crank, and G the wrist-pin, all of which may be forged or cast in one piece.

C is the balancing-disk, which, with the weighted part H, is cast in one piece, and with an opening, g, of sufficient size in which to 50 receive said crank, the said disk being placed upon the crank so that the weight H shall be

diametrically opposite the outer or free end of the crank. The part of the concave surface of the disk from a to b in said opening g is bored in a lathe or otherwise truly formed concentric with the periphery of the disk. The corresponding convex surface of the crank is turned or fitted on a circle of the same radius as that of said concave surface of the disk concentric with the journals of the shaft, on account of which, when these two surfaces are brought together, the disk will run truly when the shaft is rotated.

F is a set-screw threaded within the periphery of the disk in a radial position midway between the bars E, at the sides of said opening g , the inner end of which screw being pointed and caused to enter a conical cavity, o, in the free end of the crank, by tightening which screw the trued surfaces of said crank and disk from a to b , above mentioned, are brought firmly together, the disk being thus rigidly secured to the crank, as shown. The disk, if properly proportioned, when thus held upon the crank, will balance the weight 70 of the outer end of the latter with the wrist-pin and so much of the connecting-rod as is supported thereon, causing the whole to run smoothly:

To economize in time and labor in the matter of fitting the crank and disk together, as stated, and for another purpose, hereinafter stated, the disk is formed with a circular concentric recess, e, between the points a and b , leaving only narrow bearing-surfaces p either 85 side thereof, along which surfaces only there is actual contact between said crank and disk. The crank, where it covers said recess, is formed with a peripheral tongue or projection, r, entering said recess, but not filling the latter, space being left in said recess outside of said projection r to receive a filling, as of soft metal poured in through a hole, f, or entered in some other manner. The cavity e is formed by the usual process of coring, and the filling 90 fits snugly against the walls thereof and the edges or shoulders of the projection r of the crank, effectually preventing longitudinal motion of the disk upon the crank. Grooves or openings of other form may be cut in this part 100 of the crank to receive the filling, in addition to or without the projection r , or other means

used to increase the hold of the filling upon the crank. If desired, the entire weighted portion H of the disk may be cored out in casting, as indicated in dotted lines, and the 5 whole filled with lead, thereby increasing the weight.

Other fasteners for the disk and crank than the threaded bolt F, above mentioned, may be employed, as judgment may determine, without further invention. For instance, as shown in Fig. 4, parallel studs or bolts h may be employed in place of the bars E on either side of the crank, threaded in the disk C, and provided with a cap, j, to bear upon the free end 15 of the crank, with screw-nuts on top of said cap.

In Fig. 5 a fastener is shown in the form of a buggy-clip passing around the end of the crank, with threaded ends extending through 20 parts of the disk and provided with screw-nuts resting in cavities in said disk. By tightening said screw-nuts the disk will be firmly fastened to the crank.

Fig. 6 shows a cross-key, m, inserted in mortises formed in the bars E in position to bear 25 upon the hub of the crank, by tightening which key the parts will be bound together, as before. A small set-screw may be provided to secure the key in place in the ordinary manner.

Fig. 7 shows a form of buggy-clip bearing upon the end of the crank formed with lateral lugs k, through which short tightening-bolts h pass, threaded in the disk C, and Fig. 8 35 shows a short stout stud, n, threaded in the crank or shaft, and reaching radially through a portion of the disk into a cavity therein containing a screw-nut. By tightening said nut the disk will be firmly held to the crank.

40 Counterbalancing disks have been used upon cranks before my application for a patent of which this is the specification; but, so far as I am aware, such disks have been secured to the cranks rigidly and are not detachable. Frequently 45 the wrist-pin and the journals of the shaft become worn and have to be re-formed in a lathe, in which case it becomes exceedingly desirable to remove the balancing-disk from the crank, as with it off the shaft can be much more conveniently handled, and, besides, the worn parts can be re-turned in a much smaller lathe. The importance of my invention rests mainly in the fact that the balancing-disk may be removed from the crank at any time and as often as may be desired, and replaced without 55 having to be resifted, the fitting and fastening

being such that said disk will come back to its exact place at each time when replaced and run evenly as when first fitted; also, the disks are firmly held to the cranks and with less 60 weight of parts than is the case with others now in use.

What I claim as my invention is—

1. A shaft provided with a crank, the latter having its end attached to said shaft formed into a circular seat concentric with the journals of the shaft, in combination with a disk formed with an opening in which to receive the crank, the interior surface at one end of said opening being formed into a circular seat 70 concentric with the periphery of the disk, said circular seat of the disk having the same radius as said seat of the crank, to the end that said two seats shall touch and bear evenly together when the disk is placed upon the crank, 75 and a fastener for the disk and crank, substantially as shown and described.

2. A shaft provided with a crank, the latter having its end nearest said shaft formed into a circular seat or bearing concentric with 80 the journals of the shaft, in combination with a disk formed with an opening in which to receive the crank, the interior surface at one end of said opening being formed into a circular seat or bearing concentric with the periphery of the disk, said circular seat of the disk being formed of the same radius as said seat of the crank, to the end that said two seats shall touch and bear evenly when the disk is 85 in place upon the crank, said circular seat or bearing of the disk having a recess, and the contiguous surface of the crank having a raised part to enter said recess, and a fastener for the disk and crank, substantially as shown and described.

3. A crank-shaft and crank, the latter having a portion of its convex surface formed concentric with the journals of the shaft, in combination with a balancing-disk for said crank formed with a concave surface to fit said convex concentric surface of the crank, said concave surface having a recess, and the opposing surface of said crank having a raised part to enter said recess without filling the latter, said recess outside of said raised part being filled by another substance, and a fastener for said crank and disk, substantially as shown and described.

D. A. WOODBURY.
